UNITED STATES PATENT OFFICE.

OLE A. OWEN, OF NEW YORK, N. Y.

CIGARETTE.

1,210,198.

Specification of Letters Patent. Patented Dec. 26, 1916.

Application filed December 22, 1915. Serial No. 68,132.

To all whom it may concern:

Be it known that I, OLE A. OWEN, a citizen of the United States, residing at New York city, in the county of New York and State of New York, have invented certain new and useful Improvements in the Manufacture of Cigarettes, of which the following is a full, clear, and exact description, such as will enable others skilled in the art 10 to which it appertains to make and use the same.

This invention relates to a new and useful article of manufacture, comprising a cigarette, having permanently attached thereto a holder or socket adapted to receive the butt of a partially consumed cigarette, whereby the latter may be entirely consumed, and at the same time may serve to light the new cigarette in the holder of 20 which it has been placed.

The invention also seeks to produce an article of the character described in which a minimum amount of wrapper additional to that necessary to form a cigarette of the ordinary type is required.

Other objects of the invention will be in part obvious and in part pointed out herein-after.

The invention accordingly consists in the features of construction, combination, of elements and arrangement of parts which will be exemplified in the construction herein-after set forth, and the scope of the application of which will be indicated in the claims.

In the accompanying drawings, Figure 1 shows one of the various possible embodiments of the invention, while Figs. 2, 3 and 4 show various modifications thereof.

Referring now to the drawings in which similar reference characters are applied to similar parts throughout the several views, 2 indicates the combustible tubular wrapper of a cigarette filled with tobacco 3 throughout the major portion of its length. The mouth end is indicated at 4, and at the other, or outer, end an empty portion is left, forming a socket or holder 5, into which may be slipped the end of a cigarette or the butt 30 of a partially consumed cigarette. Owing to the tapering usually produced at the mouth end of a cigarette which has been partly consumed, it will be found that the butt of such a cigarette may be conveniently inserted into the socket, even though the former is normally of the same diameter

as the wall of the socket. It may be found convenient in practice, however, to form the socket slightly inclined outwardly to permit the ready insertion of the butts of some 60 kinds of cigarettes. Such a construction is shown in Fig. 2, in which the cigarette is provided with a flaring socket 5' which may be given any desired degree of tapering.

The cigarette may also be given a taper 65 at the mouth end, so as to increase the adaptability of convenient insertion into the socket or holder of a fresh cigarette. Cigarettes possessing this feature are shown in Figs. 3 and 4. The mouth end 4' may be 70 given any desired taper, while the socket at the other end may be of the construction shown in Fig. 1, in which it is of the same diameter as the wrapper, or it may be of the construction shown in Fig. 2, in which 75 it is provided with a flaring socket.

It will be seen that in each instance the cigarette comprises a portion normally filled with tobacco, and a socket at the outer end adapted at times to retain an end of another cigarette. By forming the socket as an extension of the wrapper of the filled portion of the cigarette, the complete article may be made in one portion, and the socket portion will be readily consumed simultaneously 85 with the butt of another cigarette which has been inserted therein. This extra portion of the wrapper will be so small that its burning will produce no discomfort to the user, as its walls are formed of the same thin paper as the body portion of the wrapper. In order to insure that the socket be kept free of any tobacco that might tend to fall therein the tobacco at this end of the cigarette may be more closely packed. 90

It will therefore be seen that there is provided a device well adapted to accomplish among others all of the ends and objects hereinbefore set forth in an exceedingly simple and efficient manner, and that structurally considered the device is of the greatest possible simplicity and is well adapted to be made at a minimum cost. 100

As many changes could be made in the above construction and many apparently 105 widely different embodiments of this invention could be made without departing from the scope thereof, it is intended that all matter contained in the above description or shown in the accompanying drawings shall 110 be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent is:

- 10 1. An article of manufacture comprising a cigarette having at its outer end a combustible cigarette holder.
- 15 2. An article of manufacture comprising a cigarette with a tubular combustible wrapper inclosing tobacco, the wrapper at the outer end of the cigarette extending outwardly beyond the tobacco, and forming a combustible socket adapted to receive and retain the end of another cigarette.
- 20 3. An article of manufacture comprising

a cigarette with a tubular combustible wrapper inclosing tobacco, the wrapper at the outer end of the cigarette extending outwardly and flaring beyond the tobacco, and forming a combustible socket adapted to receive and retain the end of another cigarette.

25 4. An article of manufacture comprising a cigarette with a tubular combustible wrapper inclosing tobacco, the wrapper at the outer end of the cigarette extending outwardly beyond the tobacco, and forming a combustible socket adapted to receive and retain the end of another cigarette, the inner end of the cigarette being tapered so as to 30 form a mouth end of decreased diameter.

In testimony whereof I affix my signature, in the presence of two witnesses.

OLE A. OWEN.
